UNITED STATES PATENT OFFICE

RICHARD BROWNE, OF MILWAUKEE, WISCONSIN, ASSIGNOR TO PHOENIX HOSIERY COMPANY, OF MILWAUKEE, WISCONSIN, A CORPORATION OF WISCONSIN

DESIGN FOR A STOCKING

Application filed July 11, 1931. Serial No. 40,506. Term of patent 3½ years.

To whom it may concern:

Be it known that I, RICHARD BROWNE, a citizen of the United States, residing at Milwaukee, in the county of Milwaukee and State of Wisconsin, have invented a new, original, and ornamental Design for Stockings, of which the following is a specification, reference being had to the accompanying drawings, forming a part thereof.

I claim:

The ornamental design for a stocking, as shown.

RICHARD BROWNE.
